UNITED STATES PATENT OFFICE.

JAMES W. LOGAN, OF CHICAGO, ILLINOIS, ASSIGNOR TO THE VULCAN OIL BURNER CORPORATION, OF NEW YORK, N. Y., A CORPORATION OF NEVADA.

OIL-BURNING APPARATUS.

Application filed June 24, 1926, Serial No. 118,138.

This invention relates to a liquid fuel burner, and it is an object of this invention to provide an apparatus which will thoroughly aerate the fuel, disseminate the same, and maintain the burning zone at a distance from the fuel feeding means.

Devices of known construction have not proven entirely satisfactory in that the fuel aerating means and parts associated therewith must be rotated at tremendous speeds in order to properly disseminate the fuel. High speed operation is not desirable, since unusual stresses are created, which are detrimental to and soon impair the operation of the device.

Further, attempts have heretofore been made to remove the combustion zone from the fuel feeding instrumentalities to avoid the necessity of subjecting the parts thereof to the injurious thermal effects, but due to features of construction and arrangement, such attempts have not heretofore been successful.

One object of the present invention is to simplify and improve the construction of devices of the character mentioned.

Another object is to provide improved means whereby the speed of rotation of the moving parts may be materially reduced without impairing the operating efficiency thereof.

A further object is to provide fuel conveying means having deflecting means associated with the end thereof to effectively remove the zone of combustion from the fuel feeding means and associated parts.

Other objects and advantages will appear from the following description of an illustrative embodiment of the present invention.

In the accompanying drawings, which illustrate a preferred embodiment of this invention and in which similar reference numerals refer to similar features in the different views:

Figure 1 is an elevational view of my improved burner shown in connection with a furnace partly broken away.

Figure 2 is a top plan view of the burner with the fire brick omitted.

Figure 3 is a side elevational view of the burner with parts broken away.

Figure 4 is an enlarged sectional view upon the line IV—IV of Figure 3.

Figure 5 is an enlarged sectional view upon the line V—V of Figure 1.

Figure 6 is an enlarged sectional view upon the line VI—VI of Figure 4.

In the illustrated embodiment of this invention, there is shown a burner comprising a pan or basin 1 mounted upon legs 2 in a furnace, the wall of which is shown broken away and which may be termed a combustion chamber. The pan 1 is provided with spaced concentric flanges 1^a and 1^b, the latter of which extends above the former. A dished shaped metal flange or support 3 is welded or secured to the exterior of the flange 1^a in flush relation with the top thereof. Suitable fire brick 4 (Figures 1 and 5) are positioned over the pan 1 and support 3. These fire bricks are preferably positioned in spaced relation as shown in Figure 5 to allow the liquid fuel to seep therethrough. The liquid fuel that seeps through the fire brick will find its way to the pan 1, most of it being drained therein by the dished shaped flange 3.

A cylindrical well or container 5 is supported upon a pedestal 6 centrally below the pan 1. A cylindrical bearing box 7 (Figure 4) is suspended in the container by means of any annular flange 7^a engaging the top thereof. This bearing is spaced from the wall of the container and from the bottom thereof for a purpose that will later appear.

A hollow centrifugal fuel feeding member or conveyor 8 is journalled at its lower end in the bearing box or socket 7. The member 8 extends through the neck formed by the flange 1^b of the pan or basin 1, and the interior thereof is in conical form and diverges upwardly, preferably having a convergence sufficient to effect a marked fuel elevation at comparatively slow speeds.

The lower bearing portion of the centrifugal fuel feeding member is externally cylindrical to fit in the bearing box or socket 7, and the same is provided with a pulley 9 just above the bearing socket 7. Above the pulley 9, the member 8 is in the form of a conical shell. It is, however, immaterial as to the exterior form of the member 8 provided that the interior thereof is of conical form. In the use of the word "conical", it should be understood as merely applied to the interior surface of the fuel feeding member. The lower end of the member 8 is open for communication with the oil container 5 for admitting the liquid fuel.

A fan 10 is secured upon the upper end

- of the fuel feeding member 8. This fan is provided with a hub 11 that surrounds the member 8, deflecting means in this instance a top plate 12, and straight blades 13 extending radially from the hub 11 and joined to the top plate 12 so that the air is directed radially thereof. The fan is located just above the fire brick as shown in Figure 1. The member 8 is provided with a depressed surface or groove 14 in a longitudinal plane through the fan and one or more fuel feeding nozzles 15 extend from the groove 14 through the space between a pair of fan blades.
- 15 A rod 16 is threaded or secured in the bottom of the liquid fuel container 5 and extends centrally through the fuel feeding member 8 and through the top 12 of the fan. A stationary heat absorbing plate 17 is supported upon the upper end of the rod 16 for shielding the fan and conveyor tube 8 from interior heat.
- 20 A liquid fuel supply pipe 18 extends into the oil container 5 for supplying liquid fuel thereto, beneath the bearing 7. A basin drain pipe 19 extends from the basin 1 to the upper portion of the container 5 and communicates with the space between the container 5 and bearing 7 for returning any 25 unconsumed oil to the container. A pipe 20 extends from the pipe 19 to a trip bucket of any usual construction (not shown) housed in a casing 21. (Figure 2).
- 25 The liquid fuel supply pipe 18 extends to a suitable pump 22 which communicates by means of a pipe 23 with a strainer 24 to which the fuel is fed from a source of supply by a pipe 25.
- 30 The pump 22 is driven by a motor 26 having a shaft 27 which is suitably connected to the pump. A pulley 28 upon the motor shaft is connected by a belt 29 with the aforementioned pulley 9 on the liquid fuel feeding tube or member. A belt tightening device 35 of usual construction may be applied to the belt 29.
- 35 No particular motor control has been illustrated beyond a switch box 31 on the trip bucket casing 21, which may be used for starting and stopping the motor.
- 40 The operation of the burner will now be set forth. When the motor is started, liquid fuel will be pumped into the container 5, and the conical fuel feeding tube 8 will elevate the fuel through centrifugal force to the nozzles 15, the top plate 12 of the fan will act as a stop for the rising fuel which will be dashed by centrifugal force into the groove 14 and through the nozzles 45 15 which rotate with the conical member 8. The fan 10 that also rotates with the conical fuel feeding tube will create a current of air that will carry the fuel some distance from the fan before it comes into the ignition or combustion zone which on account of

the action of the fan is somewhat removed therefrom. The rapid rotation of the fuel feeding tube 8 will naturally draw the liquid fuel up to the discharge points in the form of sheets so that an adequate supply of fuel 70 is always present.

75 The centrifugal force of the fuel conveyor is ordinarily sufficient to prevent the fuel from flowing through the pipe 20 to the trip bucket. However, if the burner should accidentally go out, the fuel that is discharged by the rotary conveyor would return through the pipe 19 and when the container 7 becomes sufficiently full, the fuel would flow through the pipe 20 to the trip bucket to 80 stop the motor as is well known in the art.

I am aware that many changes may be made, and numerous details of construction may be varied through a wide range without departing from the principles of this invention, and I therefore do not purpose limiting the patent granted hereon, otherwise than necessitated by the prior art.

85 I claim as my invention:

1. In a liquid fuel burner, the combination 90 with a combustion chamber, of a centrifugal member including a relatively long conical bore of sufficient divergence to effect fuel elevation at comparatively low speeds, a guide rod extending through said bore and about 95 which said member is rotatable and fuel projecting means associated with the discharge end of said conical bore.

2. In a liquid fuel burner, the combination 100 with a combustion chamber, of a centrifugal fuel conveyer operable at relatively low speeds comprising a tube having a conical bore, the largest end of said bore comprising a discharge orifice, a plurality of radial nozzles connected to the discharge end of said tube, a deflector plate associated with said end of said tube for deflecting the fuel striking it into said nozzles, a guide rod extending through said bore and connected at one end to said plate, means for rotating said tube about said rod and means for delivering liquid fuel to said conical bore including a cup-like chamber serving as a mounting for the other ends of said tube and rod.

115 3. In a liquid fuel burner, the combination 110 with a combustion chamber, of a centrifugal fuel conveyer comprising a tube having a conical bore, the largest end of said bore comprising a discharge orifice, a plurality of radial nozzles connected to the discharge end of said tube, a deflector plate connected to said end of said tube for deflecting the fuel striking the same into said nozzles, a rod extending through said bore and said deflector plate, a heat absorbing member secured to one end of said rod for protecting said deflector plate from the heat in the combustion chamber, means for rotating said tube and means for delivering liquid fuel to said conical bore including a cup- 120

like chamber serving as a mounting for the other end of said tube, said rod extending clear through said conical bore and having its other end connected to said chamber.

5. 4. In a liquid fuel burner, the combination with a combustion chamber, of a centrifugal fuel conveyer comprising a tube having a conical bore, the largest end of said bore comprising a discharge orifice, a plurality 10 of radial nozzles connected to the discharge end of said tube, a deflector plate connected to said end of said tube for deflecting the fuel striking the same into said nozzles, a rod extending through said bore and said 15 deflector plate, means for rotating said tube, and means for delivering liquid fuel to said conical bore including a cup-like chamber serving as a mounting for the other end of said tube, said rod extending clear through
- said conical bore and having its other end 20 connected to said chamber.
5. In a liquid fuel burner, the combination with a combustion chamber, of a centrifugal fuel conveyer comprising a tube having a conical bore, the largest end of 25 said bore comprising a discharge orifice, a plurality of radial nozzles associated with the discharge end of said tube, a deflector plate associated with said nozzles for deflecting the fuel striking the same into said nozzles, a rod extending through said bore and said deflector plate, means for rotating said tube about said rod, and means for delivering liquid fuel to the tube at its lower 30 end.
